UNITED STATES PATENT OFFICE.

EUGENE BRISBIN, OF BOWLING GREEN, OHIO.

PORTABLE WIRE FENCE.

SPECIFICATION forming part of Letters Patent No. 600,401, dated March 8, 1898.

Application filed March 26, 1897. Serial No. 629,363. (No model.)

To all whom it may concern:

Be it known that I, EUGENE BRISBIN, a citizen of the United States, residing at Bowling Green, in the county of Wood and State of Ohio, have invented certain new and useful Improvements in Portable Wire Fences; and I do hereby declare the following to be a full, clear, and exact description of the invention, such as will enable others skilled in the art to which it appertains to make and use the same.

This invention relates to improvements in portable fences, and more particularly to portable folding wire fences.

The object of the invention is to provide a fence of the character mentioned which shall be simple, cheap, and durable and one which is adapted to be quickly taken down or set up, as the case may be, without injury to the fence.

20 A further object of the invention is to embody in the construction of a fence simple and efficient means for retaining the line-wires thereof stretched at a proper degree of tension and also to provide improved anchoring 25 means for retaining the posts of the fence in their proper positions.

With these objects in view the invention consists, substantially, in the novel construction, combination, and arrangement of parts, 30 as will be hereinafter fully illustrated, described, and claimed.

In the accompanying drawings, Figure 1 is a perspective view of a fence constructed in accordance with the present invention, one 35 corner of the fence being illustrated to show the relation of the anchoring means thereto and the surface of the ground being shown by dotted lines in order to disclose the position of such anchoring means therebeneath. Fig. 2 is a detail perspective view of the anchoring-plate. Fig. 3 is a similar view of one 40 of the draft-rods. Fig. 4 is a detail perspective view of one of the draft-rods employed at the side of the fence.

45 Similar numerals of reference designate corresponding parts throughout the figures of the drawings.

Referring to the drawings, 1 designates the line-wires of a fence, which may be of any 50 desired gage, and each of said wires has its ends formed into loops 2 for the reception of posts 3, preferably tubular in cross-section,

for reducing the weight thereof and facilitating handling the same.

It will be noted that each panel of the fence 55 is formed of a plurality of sections disposed one above the other, and by means of this construction said sections of each of the panels may be readily folded over and upon each other when it is desired to transport the fence 60 from one locality to another, and in order that the line-wires 1 of each of the panels may be securely held together and thus retain the panels intact stay-wires 4 are employed. Each of the stay-wires 4 is formed of a single 65 strand of wire and is bent upon itself at a point substantially midway of its ends. The point at which the bend is made is preferably left open to form an eye 5, and after said eye has been formed in each of the stays 4 the 70 sides of the latter are twisted a sufficient distance from the eye 5 to prevent the line-wires 1 lying immediately adjacent to said eye 5 when said wires 1 are placed in the stays 4. After positioning one of the line-wires 1 in 75 the stay-wires 4 at a point which is somewhat near the eyes 5 the twisting of the stays 4 is then continued for a distance so as to place the next line-wire 1, which is placed in the stays 4, the required space from the first line-wire 80 twisted into the stays 4, when a second line-wire is also twisted into said stays, and this operation continued until the section of the panel being thus formed is of the required width. The next section of the panel is 85 formed in a similar manner, but previous to positioning the line-wires the stay-wires of the second section to be formed are first passed through the eyes 5 of the stays 4 of the panel which has been completed. The 90 strands of the stays 4 of the second section to be formed are then bent at a point substantially midway of their ends and twisted, as before described, the line-wires being twisted into said stays at the required spacing during the operation of forming the section. When the sections of each panel have been 95 thus formed, it will be seen that the eyes 5 of the stays 4 of both the upper and lower sections of each panel are connected together, and by means of these eyes 5 the sections are 100 hinged together, so that they may be closed over and folded upon each other for readily transporting the same. The upper ends of

the stays 4 of the upper sections, when the latter have become the required width, are bent over, as shown in the drawings, while the lower ends of the stays 4 of the lower 5 sections project downwardly, as also clearly shown. When the panels have been thus formed, it will be seen that the loops 2 in the ends of the line-wires 1 are in alinement with each other, so that to connect a plurality of 10 panels it is simply necessary to pass one of the posts 3 through the loops 2 of the meeting ends of the panels, and by means of the posts 3 it will be seen that the sections of each of the panels are retained in open position or 15 that wherein one is held above another.

For the purpose of anchoring the posts 3, so that it will be unnecessary for the same to be planted in the ground, an anchoring-plate 6 is employed and positioned at each end of 20 the fence, said plate being preferably substantially elliptical and provided with a handle 7, said handle 7 being welded or otherwise suitably secured to the plate 6, so as to form a firm connection therewith, the end of 25 the plate 6 opposite to the handle 7 being pointed to facilitate the insertion of said plate into the ground and having its edges sharpened to also enable said plate passing through the soil. The anchoring-plates 6 are further 30 provided at substantially their center with apertures 8, which apertures are provided at diametrically opposite points with notches 9, and for the purpose of connecting the anchoring-plates 6 with the posts of the fence draft- 35 rods 10 are employed. Each of the draft-rods 10 may either be solid or tubular, and formed at one end thereof is an arrow-head 11 of slightly greater diameter than the diameter of the rods 10. By this construction it will be 40 seen that the arrow-heads 11 are adapted to readily pass through the slots or openings 8 when the ends of the heads 11 are caused to register with the notches 9 of the openings 8, and after passing the heads 11 through the 45 openings 8, as described, a partial rotation is given to the rods 10, so as to place the ends of the heads out of alinement with the notches 9, whereby the draft-rods 10 are firmly secured 50 to the anchor-plates 6 and prevented being displaced therefrom. The ends of the rods 10 opposite to the arrow-heads 11 are bifurcated, and journaled in the bifurcated end of each of the rods 10 is a shaft 12, having mounted thereon at substantially its center a ratchet-wheel 55 13, a pawl 14 being pivoted to the inner end of the bifurcation and adapted to engage the teeth of the ratchet-wheel 13 for retaining the latter adjusted at different positions. A removable handle 15 may be attached to one 60 end of the shaft 12 for rotating the latter, and by reason of the crank 15 being removable it is quite obvious that a single one is all that is necessary for employment with the fence when necessary to erect the same or 65 tighten the wires thereof when the same have become slack.

A cable 16 connects each of the posts 3 at

the ends of the fence with the draft-rod 10, arranged adjacent thereto, and each end of the cable 16 is provided with a loop 17, adapted 70 to receive the upper and lower ends of the posts 3, the cable 16 passing through an opening 18, formed in the ratchet-wheel 13. By so attaching the cable 16 to the ratchet-wheel 13 it will be seen that when rotation is imparted to 75 the shaft 12 the cable 16 is wound thereon, thus imparting to the post to which the cable 16 is attached a pulling force and thereby tensioning the line-wires connected to said post. By reference to the drawings it will be seen that 80 one of the anchoring-plates 6 and the draft-bar 10, connected thereto, is arranged in alinement with each side of the fence at each end thereof, and it will be further noted that the posts 3 do not enter the ground, but simply rest thereon, the anchoring means described being sufficient to retain the posts 3 in their upright position.

In the event that the fence is of considerable length or that the same is desired to be 90 used for inclosing fields and the like wherein stock are quartered it will be necessary to brace the posts 3 at different points between the end posts of the fence, and in order that this may be accomplished side draft-rods 19 95 are positioned at different intervals, said rods 19 being substantially the same as the rods 10; but in lieu of the shaft 12 and ratchet-wheel 13 thereof spurs 20 are formed on the rods 19, around which a stay-wire 21 is 100 adapted to be coiled. The stay-wires 21 are provided in their ends opposite to those which are connected to the spurs 20 with loops 22, said loops being adapted to receive the upper 105 ends of the posts 3, and it will thus be seen that the stay-wires 21 when the proper degree of tension is imparted thereto will cause the posts throughout the length of the fence between the end posts being properly supported.

The method of constructing the herein-described fence has been already described, and it is believed the manner of setting up the same will be readily understood by those skilled in the art.

The fence as an entirety is complete when leaving the factory, and when the same has reached the point of erection it is simply necessary to open the sections of the panels and connect said panels by passing the posts 3 120 through the loops 2 of the line-wires 1. When this step has been taken, the anchoring-plates 6 are positioned in the ground adjacent to the points which the end posts of the fence will occupy, said plates inclining at substantially 125 an angle of forty-five degrees. The planting of the anchoring-plates 6 may be effected in any desired manner—such, for instance, as by the employment of a maul or sledge—and when the anchoring-plates 6 have been 130 thus positioned the draft-rods 10 are thrust into the ground at substantially the angle between the upper end of the end posts of the fence, when said posts are set up, and the

point occupied by the openings 8 of the anchoring-plates 6. When the arrow-heads 11 of the draft-rods 10 have been passed through the openings 8 of said anchoring-plates, said 5 draft-rods 10 are partially rotated, so as to place the ends of the heads 11 out of alignment with the notches 9, and thus secure the draft-rods 10 to the anchoring-plates 6. After the cables 16 have had their ends connected 10 to the end posts of the fence, said cables having been previously passed through the openings 18 in the ratchet-wheels 13, the shafts 12 are rotated, thereby winding the cables 16 upon said shafts until a proper degree of tension 15 has been imparted to the cables 16 to retain the end posts in their upright position, the pawls 14 engaging the teeth of the ratchet-wheels 13 and retaining the latter in their adjusted position. The fence is now erected, 20 and in the event that the side draft-rods 19 are employed the same are positioned in the ground in a manner similar to the draft-rods 10, it of course being necessary to employ one of the anchoring-plates 6 in connection 25 with each of the draft-rods 19 to secure the latter in the ground, as is apparent. To remove the fence for transporting the same to another point of erection, it is simply necessary to loosen the cables 16, so that the fence 30 may be taken down and the sections of the panels folded, and by extracting the anchoring-plate 6 and the draft-rods 10 and 19 the latter may be also transported to their new position and the fence erected with little difficulty.

From the foregoing description it will be seen that I have provided an exceedingly simple fence adapted to be readily folded for transportation and as readily erected when 40 necessary, and the same embodies in its construction simple and efficient means for retaining the same erected. The fence is also light and may be put up without any injury whatever to the same, and while I have described the device 16 as "cables" I wish it to be understood that this term implies anything in the nature of a rope, chain, or similar device.

Having thus described the invention, what 50 is claimed as new, and desired to be secured by Letters Patent, is—

1. A fence of the class described, comprising a plurality of sections, in combination with an anchoring-plate provided with a slot or opening 55 having notches at its sides, a draft-rod having a head at one of its ends adapted to be inserted through the opening of the anchoring-plate and the notches thereof and to be rotated so as to position said head out of alignment with the notches to prevent displacement of the draft-rod from the anchoring-plate, a shaft journaled in the draft-rod, a ratchet-wheel mounted upon said shaft and provided with an opening, a pawl also carried by the draft-rod and adapted to engage the teeth of the ratchet-wheel to lock the latter against rotation, and a cable passing 120 through the opening of the ratchet-wheel and adapted to be connected to the fence, said cable being adapted to be wound upon the shaft when the latter is rotated to retain the fence in elevated position, substantially as described.

2. A fence of the class described, comprising

a plurality of panels, in combination with an anchoring-plate provided with a slot or opening having notches at its sides, a draft-rod having a head at one of its ends adapted to be inserted through the opening of the anchoring-plate and the notches thereof and to be rotated so as to position said head out of alignment with the notches to prevent displacement of the draft-rod from the anchoring-plate, a shaft journaled in the draft-rod, and suitable connections between said shaft and the fence for retaining the latter in its erected position, substantially as described.

3. A fence of the class described, comprising a plurality of panels, in combination with anchoring-plates, draft-rods suitably connected to said anchoring-plates, shafts journaled in said draft-rods, and cables suitably connected to said shafts and also connected to the fence, 85 said cables being adapted to be wound upon said shafts for retaining the fence in erected position, substantially as described.

4. A fence of the class described, comprising a plurality of panels, in combination with anchoring-plates, draft-rods connected to said anchoring-plates, shafts journaled in said draft-rods, cables connected to said shafts and the fence and adapted to be wound upon said shafts to retain the fence in erected position, and means for locking said shafts against rotation, substantially as described.

5. A fence of the class described, comprising a plurality of panels, in combination with anchoring-plates, draft-rods connected to said anchoring-plates, shafts journaled in said draft-rods, cables connected to said shafts and the fence and adapted to be wound upon said shafts to retain the fence in erected position, ratchet-wheels mounted upon said 105 shafts, and pawls carried by the draft-rods and adapted to engage the ratchet-wheels to lock the shafts against rotation, substantially as described.

6. In a fence of the class described, the combination with the panels thereof, of an anchoring-plate provided with a slot or opening having notches at its sides, a draft-rod having a head at one of its ends adapted to be inserted through the opening of the anchoring-plate and the notches thereof and to be rotated so as to position said head out of alignment with the notches to prevent displacement of the draft-rod from the anchoring-plate, a shaft journaled in the draft-rod, a ratchet-wheel mounted upon said shaft and provided with an opening, a pawl also carried by the draft-rod and adapted to engage the teeth of the ratchet-wheel to lock the latter against rotation, and a cable passing 125 through the opening of the ratchet-wheel and adapted to be connected to the fence, said cable being adapted to be wound upon the shaft when the latter is rotated to retain the fence in elevated position, substantially as described.

7. In a fence of the class described, the com-

bination with the panels thereof, of anchoring-plates provided with openings having notches at their sides, draft-rods provided with heads adapted to be inserted through 5 the openings and notches and to be rotated so as to position said heads out of alinement with the notches of the openings, whereby the draft-rods are secured to the anchoring-plates, said draft-rods being further provided with 10 bifurcated ends, shafts journaled in said bifurcated ends, ratchet-wheels mounted upon said shafts and provided with openings, means for rotating said shafts, cables passing through the openings of the ratchet-wheels and adapted to be secured to the fence, said cables being further adapted to be wound upon the 15 shafts to retain the fence in erected position, and means for retaining the ratchet-wheels locked against rotation, substantially as described.

8. In a fence of the class described, the combination with a plurality of detachable panels provided at their ends with a series of loops adapted to receive the posts of the fence for 25 connecting the panels together, of an anchoring-plate provided with a slot or opening having notches at its edges, a draft-rod provided with a head adapted to enter the opening and notches thereof and be rotated therein so as 30 to position the head out of alinement with the notches to secure the draft-rod to the anchoring-plate, a shaft journaled in said draft-rod, a ratchet-wheel mounted upon said shaft, a cable secured to the ratchet-wheel and adapted 35 to be wound upon the shaft when the latter is rotated, said cable being connected to the fence, whereby the latter is retained in erected position when the cable is wound

upon the shaft, and means for locking the shaft against rotation, substantially as described.

9. In a fence of the class described, the combination with a plurality of panels each of which is formed of a series of sections so connected as to fold upon each other, said panels being adapted to be connected by the posts of the fence, of anchoring-plates provided with openings having notches, draft-rods provided with heads adapted to be inserted in the openings of the anchoring-plates through 50 the notches thereof and to be rotated so as to position the heads out of alinement with said notches and thereby secure the draft-rods to the anchoring-plates, shafts journaled in the draft-rods, ratchet-wheels mounted upon said 55 shafts, cables suitably connected to the shafts and also attached to the fence, whereby when said shafts are rotated the cables are adapted to be wound thereon to retain the fence in erected position, means carried by said draft- 60 rods for locking the shafts against rotation, draft-rods adapted to be located at different points throughout the length of the fence at the sides thereof, said side draft-rods being provided with spurs, and cables adapted to 65 be attached to the fence and connected to the spurs of the side draft-rods, whereby the sides of the fence are retained in erected position, substantially as described.

In testimony whereof I have signed this 70 specification in the presence of two subscribing witnesses.
